UNITED STATES PATENT OFFICE.

DOMINIC SAUDINO, OF NEW YORK, N. Y.

VENTILATED SHOE.

1,390,929.

Specification of Letters Patent. Patented Sept. 13, 1921.

Application filed February 4, 1921. Serial No. 442,448.

To all whom it may concern:

Be it known that I, DOMINIC SAUDINO, a naturalized citizen of the United States, residing at New York, in the county of New 5 York and State of New York, have invented certain new and useful Improvements in Ventilated Shoes; and I do hereby declare the following to be a full, clear, and exact description of the invention, such as will 10 enable others skilled in the art to which it appertains to make and use the same.

The invention relates to foot covering and more particularly to the type of shoes for out door wear, the purpose being to ventilate 15 the foot and keep the same cool and dry in warm weather.

The invention consists of a shoe comprising an inner sole and an outer sole, the two soles being spaced apart and having the 20 lower edge portion of the upper stitched thereto, that part of the upper spanning the space between the inner and outer soles having a row of openings formed therein and the edge portion of the inner sole having 25 openings for the ingress and the egress of air when the shoe is worn and the person is walking.

Other objects and advantages will be apparent and suggest themselves as the nature 30 of the invention is understood.

While the drawings illustrate an embodiment of the invention, it is to be understood that in adapting the same to meet different conditions and requirements, various 35 changes in the form, proportion and minor details of construction may be resorted to without departing from the nature of the invention.

Referring to the accompanying drawings 40 forming a part of the specification,

Figure 1 is a perspective view of a shoe 45 illustrative of the invention,

Fig. 2 is a cross section thereof,

Fig. 3 is a detail view showing the detachable band for closing the ventilating openings in the flap portion of the upper, and

Fig. 4 is a sectional detail on the line 4—4 of Fig. 1 looking in the direction of the arrows and showing the parts on a larger 50 scale.

Corresponding and like parts are referred to in the following description and designated in the several views of the drawings by like reference characters.

55 The term shoe is employed to designate the foot covering of any design or make for

out door wear. The invention relates more particularly to the parts associated with the ventilating feature. As shown, the shoe comprises an outer sole 1, an inner sole 2, and an upper 3. The upper 3 is stitched to the inner sole at 4. An extension of the upper 3 constitutes a flap 5 which is stitched at 6 to a scarf portion of a welt piece 7 placed against the outer sole 1 and stitched thereto at 8. The extension 5 constitutes a bellows flap and is loose to admit of contraction and expansion to insure a positive circulation of air whereby the foot is kept cool and dry in warm weather. A row of 70 openings 9 is formed in the flap 5 for the ingress and egress of air. A row of openings 10 is formed in the outer edge portion of the inner sole 2 for a like purpose. The inner sole 2 is spaced from the welt 75 piece 7, a filler 11 being interposed between the two and secured so as to prevent displacement. The filler 11 is of less width than the inner sole 2 and the welt piece 7 so as to leave an outer space 12 for the unobstructed passage of the air in entering and leaving the shoe. When walking, the flap 5 expands and contracts and results in a pumping action whereby air is positively drawn into and expelled from the shoe, 85 thereby keeping the foot cool and dry.

It is desirable at times to cover the openings 9 to exclude dust and moisture, as when traversing a dusty road or walking in the rain. For this purpose a band 13 is provided. The band 13 preferably consists of a strip of rubber of suitable length and width to inclose the flap 5 and covering the openings 9 therein. The band 13 is detachably connected with the shoe so as to be carried in the pocket when not required for immediate use. Suitable securing means, 90 such as separable fastenings 14, are provided for retaining the band 13 in position when required for use. One part of the fastening means is applied to the shoe and the other part to the band, as will be readily understood.

A shoe constructed in accordance with the invention insures a positive ventilation 105 of the foot and provides for excluding dust and moisture when necessary. The construction is such as to admit of the shoe being manufactured at about the cost of the ordinary shoe, and the completed article 110 presents a neat appearance and is light and insures a cool and dry foot.

What is claimed is:

1. In a shoe, inner and outer soles, a filler disposed between the two soles and of less width so as to provide an outer space, and an upper having a extension constituting a bellows flap which is connected to the inner and outer soles by stitching, the outer edge portion of the inner sole and said flap being provided with a row of openings for the ingress and egress of air.
2. A ventilated shoe having a row of openings in the lower portion of its upper, a

band for covering the openings in the upper, and fastening means for detachably connecting the band to the shoe and comprising complementary parts applied to the shoe and band.

In testimony whereof I affix my signature in presence of witnesses.

DOMINIC SAUDINO.
